mond T. Moloney, Chicago, Ill.

Application January 10, 1940, Serial No. 313,274

10 Claims. (Cl. 273—101.1)

The invention relates to a light responsive target shooting apparatus. Such apparatus is usually coin released for operation and used for amusement purposes in testing aiming skill of the player, who employs a light ray shooting gun or rifle which is aimed at a moving target including a light responsive means such as a photo-electric cell.

In these games, it is usual to animate the target by having it move or change direction every time the photo-electric cell is hit. Thus the target, through the game playing cycle, always moves in the same manner and a marksman or player soon achieves such skill in hitting the target that interest is lost. It is desirable during the given length of time the target operates to animate the target in one way for part of the given time of operation and in another way for the remainder of such time, and to use the gun trigger rather than the photo cell as a control in an electric circuit including the motor that drives the target, to achieve such results. In a more specific sense, to maintain and keep up player appeal, it is desirable to make the first ten shots result in a relatively complex target movement to make hits more difficult to achieve, but if all first ten shots, for example, constitute accurate hits then to arrange the control in a manner thereafter to cause a relatively simple target motion to make succeeding hits easier of accomplishment to enable the player to build up high scores in the nature of a reward for skillful handling of the first ten shots. It is also desirable to provide an improved target and motion therefor so coordinated with the light projecting gun as to achieve the best results.

The main object of the invention is to provide an improved target shooting apparatus utilizing light rays.

Another object is to provide a gun control means responsive to trigger action for regulating the drive to and change of motion for the movable target.

Still another object is to provide such control wherein the first predetermined number of shots, say ten, will cause the moving target to turn around on an axis and if all ten shots hit the photo-electric cell in the target, then to prevent such turning of the target and cause it merely to move along a path, turn around at the end of such path, and then come back to a centered position of rest and stay there just as the operation of the game ceases.

Another object is to provide a shut-off control to terminate operation of the game after a cer-

tain interval of operation in case the first ten shots do not all achieve photo cell hits.

Another object of the invention is to provide a carrier for conveying a target back and forth along a certain path, but to permit turning thereof, by novel means, on a vertical axis and automatic change of direction of the target.

Another object is to provide an improved electrical circuit for a game of this class, wherein the target operating means and gun are coordinated to produce novel results.

Other important objects will become apparent to those skilled in this art as the disclosure is more fully made.

Briefly, in one preferred form of the invention these desirable objects may be achieved in providing a cabinet carrying a track or guideway along which a carrier is moved by a chain or belt driven from an electric motor. The carrier supports a novel target which may simulate a bull and includes a photo-electric cell, there being means in the motor circuit controlled by operation of the light ray gun trigger to cause the target to turn around and go in an opposite direction every time a hit is achieved during a first cycle or predetermined number or succession of shots. In case the first ten shots are not all hits the game remains in operation for a time controlled interval and for the remaining shots available during the interval the target turns and reverses upon every hit. However, should all of the first ten shots be hits, then different control means becomes operative in the circuit to cause the target to move straight away to the end of its guideway, then turn around and return to a stopped, centered position on the guideway just as the game ends upon opening of the circuit, it being understood, that during such latter straight-away movement of the target the player may rapidly shoot at the target as fast as he can pull the trigger to build up a large number of hits for scoring purposes.

The complete game organization thus embodies a light ray gun, the trigger of which controls circuits to operate the target in one manner from the motor during one cycle of operation, and in a different manner for another cycle of operation, the circuit being operative upon operation of a coin release slide and running until automatically stopped. Separate units are a trigger mechanism, step-up mechanism, release mechanism, target mechanism, reversing motor control, and a novel circuit, all as will later more fully appear.

In the drawings, showing one practicable form of the invention:

Figure 1 is a general perspective view of the target cabinet and remotely positionable light ray projecting gun and the connecting electric cable for circuit wires;

Figure 2 is a front elevational view of the target means placed in the cabinet with the front panel of the latter removed;

Figure 3 is a plan view of the same mechanism;

Figure 4 is an end elevational view of the same mechanism, partly in section, taken along the line 4-4 of Figure 3, looking in the indicated direction;

Figure 5 is an enlarged, plan detail view taken from line 5-5 of Figure 2;

Figure 6 is an enlarged detail plan view taken from line 6-6 of Figure 4;

Figure 7 is a vertical sectional view through the target carrier;

Figure 8 is an enlarged perspective view of the trigger control means of the gun;

Figure 9 is an enlarged perspective view of a step-up unit;

Figure 10 is a perspective view of a motor control unit; and,

Figure 11 is a drawing of an electrical wiring diagram to show how all parts are coordinated.

Generally, the improved apparatus comprises a target containing cabinet 15 and a light ray shooting gun or rifle 16. The front wall of the cabinet may be hinged back to expose the parts shown in Figure 2, which parts will now be described. See also Figures 3 and 4. Opposite end frame brackets or supports 17 are rigidly mounted in the cabinet, said supports securely carrying in fixed position two, horizontal, spaced, parallel bars 18 which constitute a track or guide-way for a target carrier. This carrier, or carriage, appears at 19 in channel section and is disposed vertically with its upper portion carrying two rigid, spaced brackets 20 each supporting a roller 21 turnable on a vertical axis to roll on the outside vertical face of the upper guide bar 18. The lower portion of the carriage 19 carries two spaced rollers 22 turnable on a horizontal axis to roll on the top face of the lower guide bar 18. In this fashion the carriage is slidably positioned on the parallel guide bars 18 for to and fro movement.

Looking to Figure 7 it will be seen that extending upwardly through the channel flanges of the carriage 19 is a tube or pipe 23 securely anchored therein and extending well thereabove. Around this tube the lower carriage flange supports a bearing 24 for journaling a quill shaft 25 surrounding the tube 23, said latter shaft having a portion of somewhat larger diameter disposed well above the carrier 19 and formed to carry a U-shaped holder 26 for a pair of opposite aligned lenses 27. The stationary tube 23 extends up into said holder where it carries an appropriate socket and support 28 for a photo-electric cell or lamp 29. Opposite parts of the U-bracket or holder 27 carry opposite or respective sides of a target element, which in this instance simulates a bull 30, the lenses 27 being respectively exposed on its opposite sides and registering with the photo-electric cell 29. A cable of two conductor wires 31 leads from the lamp 29 to an amplifier unit 32 (see Figure 11) suitably located within the cabinet 15. This cable 31 is of sufficient length to provide neces-

sary slack when the carrier 19 moves from one end to the other of the track or guide structure 18. The bull 30, and holder 26 turn as a unit with the shaft 25, whereas the inner shaft or tube 23 and the photo-cell 29 carried thereon do not turn, the whole structure of bull and lamp, however, moving translationally as a unit with the travel of the carriage 19. The means for moving this carriage unit along the track guide-way will now be described.

Above the top flange of the carriage 19 the turnable shaft 25 has fast thereon a gear 33, said gear being in mesh with a larger gear 34 fast on a vertical shaft 35 turnably carried in the upper and lower flanges of the carriage 19. Also made fast to said shaft 35, between its ends, is a laterally disposed lever 36 which is passed through a large opening 37 to the rear side of the carriage where the lever is universally connected by a gimbal joint 38 to a link 39. This link 39 at its opposite end is loosely and pivotally connected by a pin 40 to the upper run of a roller chain 41. This chain is endless and at its left hand end is trained around an idler sprocket wheel 42 journaled in an end bracket 43 on an end support 17, while the other or right hand end of the chain is trained around a drive sprocket wheel 44 carried by a shaft 45 journaled in brackets 46 supported by a shelf 47. The shaft 45 has fast thereon a large worm gear 48 meshing a small worm gear 49 on the shaft 50 of an electric motor 51 mounted on the shelf 47. The motor 51 is reversible and drives in either direction.

As viewed in Figures 2 and 3 it may be assumed the upper run of the chain 41 is being driven to the left. By means of the pull transmitted from the link 39, through lever 36 and shaft 35 the carriage 19 is pulled to the left along its guide tracks 18. When the direction of movement of the drive chain 41 is reversed, that is to the right, or if the pivotal connection 40 runs over the left hand sprocket wheel 42, it follows that the link 39 will then exert a pushing force on the carriage 19 and push it to the right along the guide tracks 18. Such pushing force, by link 39 will swing the lever 36 clockwise and turn the shaft 35 and its gear 34 which in turn will rotate the gear 33 causing the shaft 25, lens support 26 and the target image 30 to rotate counterclockwise. This turning movement of the shaft 25 is limited in opposite directions by a stop member 52 fast on and turnable with the shaft 25 above the gear 33 in a position to abut a yieldable shock absorbing abutment 53 mounted on the top flange of the carriage 19. With the link 39 exerting a pushing force the carriage 19 will then move to the right.

As seen in Figures 2, 3 and 11 the carriage 19 carries a rider or shoe 54 having opposite upturned ends adapted to ride over insulated wheels carried on a center, blade contact switch 55, a left hand similar switch 55 and a right hand similar switch 55. These switches are labeled 55C (center); 55R (right) and 55L (left). Each of these three switches is closed except when opened by the shoe 54 and all are mounted in an insulated manner on the rear face of the lower rail bar 18, as shown.

The gun 16 embodies a novel trigger mechanism for operating certain switches to control the circuit shown in Figure 11 and while such trigger mechanism per se is described and claimed in co-pending Breitenstein application Serial No. 313,273, filed January 10, 1940, it will, nevertheless,

less, to a proper understanding of the present disclosure, be necessary briefly to describe said trigger mechanism herein.

Referring to Figure 8 this trigger mechanism embodies a frame 56 having a wall 57, carrying a finger trigger 58 to be pulled against spring pressure. Pivotally connected to the upper end of the trigger is a longitudinal link 59 having a long slot 60 in its forward end. A bell crank lever 61 is pivoted at 62 to the wall 57 and carries a pin 63 at its upper end passed through the rear end of the slot 60. The forwardly extending arm of the bell crank 61 has its free end formed with a cut away step 64 and therebelow with a stop tail 65. A spring 66 holds a vertical latch lever 67 against the bell crank 61, as shown, said lever having its lower end bent to be positioned over the tail 65 and against the stepped end of the bell crank arm. The latch lever 67 is pivoted by a pin 68 to the frame 57 and at its upper end carries a headed pin 69 passed into the slot 60 of the link 59.

The pin 63 pivotally carries at a point between its ends, a lever 70 the front end of which carries a lateral sleeve 71 made of insulation, and the rear end of which lever has a portion 72 which acts as a pawl to engage the notches formed by teeth on a ratchet wheel 73 turnably carried on the wall 57. A spring 74 connects between the bell crank 61 near its pivot 62, and the rear end of lever 70 to hold said portion 72 toward the ratchet wheel 73. A pull spring 75 connects between the pin 63 and the pivot pin of the trigger 58. This ratchet wheel 73 is turnable from a starting position determined by a boss 76 on the wheel and an abutment pin 77 on the frame 57. A spring is energized when the wheel leaves this starting position and such power serves to return the wheel to the starting position when it is released. A lever 78 is pivoted intermediate its ends on the wall 57 and has a rear end 79 bent to act as a holding dog for the ratchet wheel teeth. This lever 78 at its rear end passes under a portion of the rear end 72 of the lever 70 so that when end 79 is raised free of the ratchet wheel the part 72 of the lever 70 will also be raised clear of the wheel 73 thus enabling the latter to be restored to the starting position. The front end of the releaser lever 78 is pivotally connected to the core 80 of a releaser coil 81, which is called the gun reset coil and is mounted on the frame plate 56, as shown in Figure 8.

The ratchet wheel 73 in the disclosed embodiment of the invention is formed with such a number of teeth 82 as to create ten effective notches for step-up by the pawl 72. Said wheel, after the final notch, has a flat portion 83 to prevent the pawl 72 from dropping when riding said portion 83 for a purpose to be made known. The link 59 at its rear end has an upstanding portion carrying a lateral part 84 made of insulation material. The part 84 is like the part 71 already described. The frame 57 carries a laminated insulation pack 85 for mounting an upper spring blade 86, a middle spring blade 87 and a lower spring blade 88 (see also Figure 11); these blades forming normally gapped apart contact switches 89 and 90. The barrel of the gun carries an electric lamp 91 and light projection lenses 92.

Generally, it will be now stated, for the time being, that when the game is released for use, the first ten pulls of the trigger 58 through the link 59 and associated mechanism cause the parts 71 and 84 to close the respective switches 89 and 90 but because of the action of a control means 70

yet to be described, only the switch 89 is in a hot circuit and consequently the lamp 91 is lighted only from said switch and shots or trigger pulls after said first ten cause the other switch 90 to be in a hot circuit and effective to light the lamp.

The control mechanism causing such alternation in switch operation is shown in Figures 9 and 11, and is referred to herein as a 1 to 10 control unit or commutator. This unit comprises a bracket 93 positionable in any desired place in the cabinet and carries a smaller bracket 94 for mounting an electromagnet coil 95 with the usual core to which is pivotally connected a lever 96 guided at its upper end in a slot 97 in the bracket 94, while its lower end is pivotally connected to a pawl arm 98 pulled by a spring 99 upwardly against a stop pin 100 carried on the bracket 93. The pawl arm 98 engages the teeth of a ratchet wheel 101 fast on a shaft 102 journaled in the bracket 93, which shaft on the back side of the bracket 93 carries fast thereon a conductor wiper arm 103. The ratchet wheel has enough teeth to provide for ten step-ups, said wheel being returnable by a spring 104 to an initial starting position. The arm 103 wipes over a conductor arc 105 fastened to the back side of the bracket 93, it being understood, of course, that the bracket 93 is made of some suitable non-conductor material. The parts 103, 105 constitute a step-up commutator. A dog 106 is pivotally mounted in a suitable position on the bracket 93 to engage the teeth of the ratchet wheel 101 and prevent retrograde movement thereof, a spring 107 serving to hold the dog 106 toward the wheel. Another sub-bracket 108 carries an electromagnetic coil 109 to cooperate with an armature portion 110 on the lever arm 106 to raise the latter from the wheel 101 and free it for return rotation to its initial starting position, said coil 109 being termed the step-up reset.

An "on and off" unit is shown in Figures 10 and 11, its purpose being to control the reversibility of the motor 51. Said unit comprises a bracket 110 positionable in any desired place in the cabinet, which bracket carries an electromagnetic coil 112 having a reciprocating core 113 pivotally connected to a lever 114 mounted between its ends for rocking motion on a transverse shaft 115 fixed on the bracket 111. Turnable on said shaft is a ratchet wheel 116 and also spaced therefrom, a star wheel 117, the latter having half as many points as there are teeth on the ratchet wheel 116 so that a 2 to 1 relationship exists between the teeth on the wheels 116 and 117.

The lower end of the lever 114 pivotally carries a pawl 118 pulled to action against the teeth on the wheel 116 by a pull spring 119. A spring pulled pivoted dog 120 prevents retrograde movement of the ratchet wheel 116. A spring blade switch 121 is proximately positioned to the star wheel 117, one blade of the said switch engaging the points thereof to separate and open the switch, or, when said one blade seats between the points of the star wheel, the said switch 121 is closed. One step of the ratchet wheel 116 turns the star wheel 117 half a step and as a result the switch 121 is alternately opened and closed. One side of the switch 121 is in circuit with the motor 51 and the other side with a reversing relay 122, said relay serving to change the positions of contact arms 123, 124 electrically connectible with the motor field coil 125. In Figure 11, the dotted

lines show the changed positions of the switch arms 123, 124, and their action is to reverse the flow of electric current through the field coil 125. It is by such means that the direction of rotation of the motor 51 is changed and consequently there is also changed the direction of travel of the chain 41 for the target carrier.

A coin released chute 126, of conventional type, is indicated in Figure 11, which as viewed is moved from right to left. Positioned in the path of movement of the chute 126 is the wedge shaped end of the center blade 121 of a blade contact switch 128 and a blade contact switch 129, the former in the position shown being closed, and the latter open. Another blade contact switch 130 having a wedge end on one blade to be engaged by the coin chute is also provided, which switch is open when the chute 126 is in its right hand position. A trigger relay 131 is in circuit with one side of the switch 130, said relay controlling a switch arm 132 which in the dotted closed position sends current to an impulse relay 133 from a condenser 134 in the amplifier 32, such current serving to energize the relay 133 as just stated, thereby closing a pair of impulse relay switches 135 and 136. The amplifier 32 includes an electromagnetic relay coil 137 responsive to a flash of light acting on the photo-electric cell 29, said relay 137 when energized acting to close a switch 138.

Still looking at Figure 11 it will be seen that the circuit also includes a clock switch 139 in the motor circuit to permit current to flow to the motor for a certain predetermined interval of time.

A "one to ten" hold-in relay 140 is in circuit with the commutator arc 105 and when energized holds closed three switches 141, 142 and 143. These switches regulate flow of current to a right stop relay 144R and a left stop relay 144L, said relays when energized respectively acting to close switches 145R and 145L and also close switches 146R and 146L.

The source of energy comprises a plus line 147 and a minus line 148. The description of the details of the organization has now been completed and accordingly there will next be summarized the mode of operation and manner of use.

The starting positions are shown in Figure 11 where the target carriage rider 54 is centered between the ends of the track 18, thus causing the switch 55C to be held open. The coin chute 126 is in its right hand position and as a result switches 129 and 130 are open, while switch 128 is closed. To condition the machine for play, the coin chute 126 is moved to the left to break the circuit through switch 128 and make a circuit through the switch 129. Closing of switch 129 conditions a circuit through the gun reset coil 81 and the step-up reset coil 109. Movement of the coin chute 126 to the left will also cause the said chute to engage and close the switch 130, whereupon current will flow from line 147 through a wire 148' through the switch 130 and into the trigger relay 131 energizing the latter and causing the switch 132 to be moved to its closed position shown in dotted lines. With the switch 132 closed current flows from the condenser 134 in the amplifier 32 into the impulse relay 133 energizing the latter and causing the two impulse relay switches 135, 136 to be closed.

Current will now flow from the plus side 147 of the line through the switch 135 by way of a 75

conductor 135' through the closed switch 129, through the gun reset coil 81, to operate the lever 78 and cause restoration of the ratchet wheel 73 to its initial starting position, said wheel having been stepped during the previous playing of the machine. At the same time the current flows through the step-up reset coil 109 energizing the latter so that dog 106 is moved to free the ratchet wheel 101 to enable its restoration to the zero starting position. Return of this ratchet wheel moves the wiper arm 103 back to its starting position on the conductor arc 105. In this manner the commutator 103 is reset at the same time with the gun. With the arm 103 in starting position on the arc 105 a circuit is completed through the "1 to 10" hold-in relay 140 to energize same. This causes the switches 141, 142 and 143 to pull up and close and put the "on and off" coil 112 in circuit through the switch 141, and through the switches 142 and 143 to energize the coils of the stop relays 144R and 144L and thus close their respective relay switches 145R and 146R, and 145L and 146L. The time control switch 139 was, of course, closed when the coin chute 126 was moved to the left and such switch will be fixed in accordance with the approximate time it would take to achieve the maximum number of target hits.

The gun 16 is used to project a beam of light to the photo-electric cell 29 as indicated in Figures 1 and 11. When the trigger 58 of the gun is pulled back a circuit is completed through the switch 89, closed by action of link 59 on lever arm 70, said switch 89 allowing current to flow through the trigger relay 131 and thereby pull up on relay switch 132 which completes a circuit from the condenser 134 through the impulse relay coil 133. Under normal conditions, when the trigger relay 131 is not energized, as when the trigger mechanism is not operated or the switch 89 is in a cold circuit, then current from the amplifier 32 is stored up in the condenser 134. When the relay switch 132 is pulled up as aforesaid by energization of the trigger relay 131, the current stored in the condenser 134 is released in one jolt into the impulse relay coil 133, said current from the condenser 134 being thereafter dissipated and ineffective. After the coin chute 126 has reset the parts heretofore mentioned and has been retracted to the right, the switch 128 is again closed and switches 129 and 130 are open during the playing of the game.

The impulse relay switches 135 and 136 are momentarily pulled up by the impulse relay 133 to complete a circuit from the plus side 147 of the line or source of energy through switch 135 and coin chute switch 128 and the gun lamp 91, the latter sending a beam or flash of light which is directed through the gun barrel 16; the same current flowing through the switch 135 into the "on and off" relay 112 and by way of a conductor 141A through the relay switch 141 which is normally disposed to complete the circuit back to the minus side 148 of the line by way of a conductor 141B through the relay switch 146R also normally disposed in circuit completing condition. The "on and off" unit of Figure 10 controls the reversibility of the drive motor 51 and when coil 112 is energized the mechanism controlled thereby operates the star wheel 117 and as shown in Figure 11, regulates opening and closing of the blade contact switch 121.

As seen in Figure 11 the motor 51 will operate in one direction and when the current is allowed to flow through the switch 121 the reversing relay 122 will be energized, thereby changing contact switch arms 123 and 124 to the dotted line position to change the flow of current through the field coil 128. This change of flow of current reverses the direction of rotation of the motor 51 and consequently reverses the direction of movement of the target moving chain 41 and turns the target image 38 about in the manner heretofore described.

If the flash of light is accurately directed by the player or marksman and it hits the photo-electric cell 28, the relay 137 on the amplifier 32 will be energized and close the relay switch 138. A circuit is then made through the switch 138 and impulse relay switch 138 to the coil 95 of the commutator to advance its wiper arm 103 one step along the conductor arc 105. In practice for scoring hits by means of indicators, contact points would be arranged alongside the arc 105 for the wiper 103 to engage and thus close scoring indicator circuits in any manner open to those skilled in the art.

The marksman must release the trigger 58 of the gun in order to allow the lever 61 to return under pull of the spring 78. The swing of the lever 61 clockwise will cause the extension 72 of lever arm 78 to step the ratchet wheel 73 one step clockwise. The switch 88 remains closed as long as the trigger 58 is held back and will only open when the trigger is returned to its normal position. Such return movement of the trigger will pull the link 59 to the right and cause the left hand end of the slot 60 to engage the pin 69 carried at the upper end of the latch 67 and rock the latter clockwise about its pivot out of engagement with the step 84 of the lever 61. The lever 61 is now free to rock and by its movement will abut extension 72 of the arm 78 against the ratchet wheel 73 thereby raising the right hand end of the arm 78 against the pull of the spring 74 and lowering the sleeve 71 at the opposite end of the arm 78 and cause opening of the trigger switch 88.

After the tenth pull of the trigger 58, the pawl portion 72 of the lever arm 78 cannot drop since there are no teeth 82 after number ten on the ratchet wheel 73. At this point the portion 72 rides the flat surface 83 and hence the trigger is rendered ineffective to close the switch 88 and the game would normally be over. However, if the marksman has achieved a hit each time he shot the first ten shots, the wiper 103 will have traveled off the contact 105, thus deenergizing the 1 to 10 hold-in relay 140 to release the switches 141, 142 and 143. Switch 141 cuts off current to the "on and off" coil 112 which is not used after ten shots, and causes current to flow through a conductor 141C into the over ten trigger switch 88. Each time the trigger 58 is pulled, the laterally extending arm 84 carried by link 59 will bear against the switch 88 to close contact on said switch and allow current to flow to trigger relay 131 so as to record such succeeding hits, if desired, through auxiliary contact buttons associated with the commutator arm 103.

Switch 143 breaks the direct flow of current from the line through right stop relay coil 144R, but it is self-held by switch 145R, allowing current to pass through the coil 144R into the track switch 55R and back to the line by way of a conductor 55'. The switch 142 breaks the circuit

to left stop relay coil 144L which is self-held by switch 145L and track switch 55L.

The "on and off" unit 117 being out of use, the motor 51 continues to rotate and drive the chain 41 in a normal manner, the target 38 turning about only when the carriage 19 reaches the end of its run on tracks 18, the link 39 being pulled over the sprocket wheel 42 and causing a pushing action on the link 39 to rotate the target about the vertical axis of the shaft 25 as has been described. In the meantime, as the target so moves, the flash of light from the gun may be directed into the photo-electric cell 28 in rapid fire or machine gun fashion to build up a high score in the nature of an award for having skillfully fired the first ten shots.

When the carriage 19 reaches the left hand end of the track 18, the rider 54 on said carriage will bear down on the switch 55L, breaking current to the coil 144L, opening the switch 145L and 146L. When the carriage 19 reaches the right hand end of the track 18 the rider 54 breaks circuit through the switch 55R and coil 144R and cause opening of the switches 145R and 146R. At this stage, the only thing that allows the continued operation of the motor is the flow of current from the motor through the switch 55C at the center of the track 18 and through the conductor 55' back to the line. Therefore, when the carriage reaches the center of its run the switch 55C is broken and the motor 51 shuts off and the game is ended with the target centered between the ends of the track in position ready for initiation of a succeeding operation of the game.

When the required ten successive hits through switch 88 and wiper 103 are not achieved, it is then that the time clock controlled switch 138 serves to open the circuit and stop the game, the timing being so arranged that the target will end up in its centered position.

It must now be appreciated that an improved, compact, simple and fool-proof target machine for the purposes stated, has been provided, such machine achieving all of the desirable objects heretofore recited.

It is the intention to cover herein all changes and modifications of the example chosen for purposes of the disclosure, which do not in material respects constitute departures from the spirit and scope of the invention as defined in the following claims.

What is claimed is:

1. A target shooting apparatus comprising a horizontal track, a carriage movable therealong in either direction, a target, means supporting the target on the carriage for movement therewith and for relative turning movement, a gun including a trigger and a normally open switch in a first circuit, a reversible electric motor including connections for driving the target along the track, another circuit including the switch and motor, a photo-electric cell in another circuit and associated with the target, an "on and off" unit to cause reversal of the motor and change in direction of travel of the carriage, a step-up commutator in another circuit responsive to closing of the switch and a ray of light from the gun hitting the photo-cell to operate the "on and off" unit, step-up control means in the gun whereby the switch can cause operation of the commutator for only a predetermined number of steps and then become inoperative so that thereafter the motor cannot be reversed, and means to keep the motor running for a pre-

determined time when the commutator is no longer effective.

2. A target shooting apparatus comprising a horizontal track, a carriage movable therealong in either direction, a target, means supporting the target on the carriage for movement therewith and for relative turning movement, a gun including a trigger and a normally open switch in a first circuit, a reversible electric motor including connections for driving the target along the track, another circuit including the switch and motor, a photo-electric cell in another circuit associated with the target, an "on and off" unit to cause reversal of the motor and change in direction of travel of the carriage, a step-up commutator in another circuit responsive to closing of the switch and a ray of light from the gun hitting the photo-cell to operate the "on and off" unit, step-up control means in the gun whereby the switch can cause operation of the commutator for only a predetermined number of steps and then become inoperative so that thereafter the motor cannot be reversed, means to keep the motor running for a certain interval after the commutator is no longer effective, other normally open switches in still another circuit, a coin chute for closing said latter switches, and electromagnetic means operable when said latter switches are closed to reset the step-up commutator and step-up control means in the gun to initial starting positions.

3. A target shooting apparatus comprising a gun having trigger means to close a switch in a first circuit, a target carriage movable in either direction along a path of movement, a reversible electric motor in another circuit controlled from the gun switch and the target being connected to be driven by said motor, a target movable with and turnable on the carriage, and means in the gun and first circuit whereby a predetermined number of successive closings of the switch causes the motor to be reversed for each such closing to reverse the travel of the carriage and result in turning the target and to keep the motor running without such reversal after the said number of switch closings to move the carriage back and forth for a certain additional period, and means in another circuit controlled by the travel of the carriage to shut off the motor at the termination of such period.

4. A target shooting apparatus comprising a gun having trigger means to close a switch in a first circuit, a target carriage movable in either direction along a path of movement, a reversible electric motor in another circuit controlled by the gun switch and the target being connected to be driven by said motor, a target movable with and turnable on the carriage, a step-up commutator in another circuit, and means controlled by the gun trigger means whereby the motor is reversed when the trigger means is operated while current is passing through the commutator and not being reversible when the commutator is ineffective and current does not pass therethrough, and means to keep the motor running irreversibly for an interval of time after the commutator is ineffective.

5. A light shooting target game including a gun having a lamp and a pair of normally open switches disposed in a circuit with a source of energy, a reversible motor in another circuit, a target including a track having a carriage movable to and fro therealong, means carrying the target on the carriage for turning motion thereon while moving therewith, a photo-electric cell on the carriage and disposed in another circuit,

means to drive the carriage from the motor and turn the target, trigger mechanism to close the gun switches, means operated by said mechanism to control the switches whereby first one thereof is effective for a predetermined number of shots to light the lamp and thereafter the other switch being effective to light the lamp for the remainder of the game cycle, a step-up commutator in another circuit operable upon closing of the first switch and a ray of light from the gun hitting the photo-cell, an on and off motor control unit in another circuit operable when the first trigger switch closes when hot to reverse the motor and change direction of travel of the carriage and to turn the target every time during the first predetermined number of trigger operations if the commutator passes current, said commutator thereafter cutting out the circuit to the on and off motor control from the first switch and enabling the second trigger switch to cause lighting of the lamp, and means operable when the commutator is ineffective to keep the motor operating irreversibly.

6. A light shooting target game embodying a circuit with a source of energy and including a lamp, a reversible motor in another circuit and a pair of gun trigger closed switches to light the lamp, means controlled by the trigger to close said switches, a target movable along a track by the motor and including a photo-cell, an electromagnetically operated step-up commutator in another circuit to cause a first predetermined number of trigger pulls to light the lamp as the result of the closing of one of the switches, motor control means operable at the same time from closing of the first switch to reverse the motor every time said first switch closes while it is in circuit, said commutator when fully stepped up causing the first switch to be in a cold circuit to make ineffective the motor control means and stop reversing of the motor, said second switch thereafter becoming effective in its circuit for the remaining time the game can be played to light the lamp, and means to keep the motor running irreversibly after the commutator is ineffective.

7. A light shooting target game embodying a circuit with a source of energy and including a lamp, a reversible motor in another circuit and a pair of gun trigger closed switches to light the lamp, means controlled by the trigger to close said switches, a target movable along a track by the motor and including a photo-cell, an electromagnetically operated step-up commutator in another circuit to cause a first predetermined number of trigger pulls to light the lamp as the result of the closing of one of the switches, motor control means operable at the same time from closing of the first switch to reverse the motor every time said first switch closes while it is in circuit, said commutator when fully stepped up causing the first switch to be in a cold circuit to make ineffective the motor control means and stop reversing of the motor, said second switch thereafter becoming effective in the circuit for the remaining time the game can be played to light the lamp, means to keep the motor running irreversibly after the commutator is ineffective, and other means controlled by travel of the target to keep the motor running irreversibly and eventually open its circuit to stop the motor and bring the target to a position of rest.

8. A light shooting target game having a trav-

eling target, a reversible motor in a circuit to drive same, a photo-cell in another circuit associated with the target, a gun including a lamp and a pair of switches normally open in another circuit, trigger controlled step-up means in the gun to close said switches, means whereby one of the switches is hot for a predetermined number of trigger pulls to light the lamp and thereafter the other switch becomes hot to light the lamp, a motor control unit operable when one switch is closed to alternate direction of rotation of the motor, and a step-up commutator in another circuit operable from either switch when the photo-cell is energized by a beam of light from the gun, said commutator when fully stepped up and not passing current acting to cut out the motor control unit and prevent reversing of the motor thereafter, and means to keep the motor running irreversibly when the commutator is ineffective for a period of time.

9. A light shooting target game having a traveling target, a reversible motor in a circuit to drive same, a photo-cell in another circuit and associated with the target, a gun including a lamp and a pair of switches normally open in another circuit, trigger controlled step-up means in the gun to close said switches, means in said gun circuit whereby one of the switches is hot for a predetermined number of trigger pulls to light the lamp and thereafter the other switch becomes hot to light the lamp, a motor control unit operable when one switch is closed to alternate direction of rotation of the motor, and a step-up commutator operable when the photo-cell is energized by a beam of light from the gun, said commutator when fully stepped up and not passing current acting to cut out the motor

control unit and prevent reversing of the motor thereafter, means controlled by the travel of the target to keep the motor running irreversibly for a while when the commutator is ineffective, and time controlled means to open the motor circuit and stop the motor and target in the event the commutator is still effective.

10. A light shooting target game having a traveling target, a reversible motor in a circuit to drive same, a photo-cell in another circuit and associated with the target, a gun including a lamp and a pair of switches normally open in another circuit, trigger controlled step-up means in the gun to close said switches, means whereby one of the switches is hot for a predetermined number of trigger pulls to light the lamp and thereafter the other switch becomes hot to light the lamp, a motor control unit operable when one switch is closed to alternate direction of rotation of the motor, and a step-up commutator operable from either switch when the photo-cell is energized by a beam of light from the gun, said commutator when fully stepped up and not passing current acting to cut out the motor control unit and prevent reversing of the motor thereafter, means to keep the motor running for a while when the second switch is hot either with the commutator effective or ineffective to pass current, and manually controlled switches in another circuit operative after the motor has been stopped and a new game cycle is to be initiated to reset the trigger step-up means and step-up commutator to initial starting positions.
